UNITED STATES PATENT OFFICE.

BERNARD M. ELY, OF TROY, OHIO.

GRINDING APPARATUS.

Application filed May 3, 1923. Serial No. 636,405.

To all whom it may concern:

Be it known that I, BERNARD M. ELY, a citizen of the United States of America, residing at Troy, county of Miami, and State of Ohio, have invented certain new and useful Improvements in Grinding Apparatus, of which the following is a full, clear, and exact description.

This invention relates to an improved form of chopping or grinding apparatus.

One of the principal objects of the invention is to provide an improved form of apparatus for grinding meat, and the like, which is efficient in its operation, simple in construction, easy of assembly, and long lived.

Another object of the invention is to provide an improved form of knife and plate construction for use in apparatus of this character.

Other objects and advantages of the invention will be apparent from the description set out below when taken in connection with the accompanying drawing.

In the drawing, in which like characters of reference designate like parts throughout the several views thereof;

Fig. 1 is a side elevation of a meat chopper or grinder, constructed in accordance with this invention, certain parts thereof being shown in section to more clearly disclose the invention;

Fig. 2 is a side elevation of one element of the invention; and

Fig. 3 is an end view of the worm forming a part of the meat grinder.

This meat grinder comprises a chopper cylinder 10, which is adapted to receive the meat, or other material to be ground.

Mounted in this chopper cylinder is a worm 11, one end of which is provided with a shaft which is suitably journaled within the bearing 12, which also acts to receive the thrust of the shaft during operation, the free outer end of the shaft being provided with flattened faces as shown at 13, to receive an operating handle, not shown, by means of which the worm may be rotated to force the meat, or other material, along the chopper cylinder.

The other end of the chopper cylinder is closed by means of a removable, perforated, plate 15, which seats within a recess 16, in the end of the chopper cylinder; being held firmly against the shoulder 17, by means of a retaining ring or sleeve 18, which is

threadedly mounted on the chopper cylinder, a hand wheel 19 being provided for rotating the sleeve 18 to permit removal of the plate 15, or to clamp that plate tightly in operative position.

The plate 15 is provided, centrally, with an opening surrounded by an outwardly extending hollow boss 25, the plate and boss thus having a passage 26 extending therethrough, which passage is adapted to receive the stud 27. The inner end of this stud has flattened faces, as shown most clearly in Fig. 2, this inner end of the stud being preferably substantially square in cross section. This inner end of the stud is also provided with a circular flange or rib 30, which divides the squared end of the stud into two parts 31 and 32. The part 31 is adapted to receive the knife 35, which is provided with a square hole or passage therethrough, a driving connection thus being secured between the stud and knife when the knife is mounted in position. The portion 32 of the squared end of the stud, when the device is in operative position, extends into a squared socket within the cooperating end of the worm 11, driving connection thus being established between the worm and the stud, and the knife carried by the stud.

The worm 11 is preferably provided with a cylindrical socket 37, as shown most clearly in Fig. 3, which is internally threaded, and which has threadedly mounted therein a sleeve 38, having a squared passage 39 therethrough adapted to receive the squared portion 32 of the stud. As shown in Figs. 1 and 3 the sleeve 38 is also recessed to receive the flange 30, this recess being designated by the numeral 40.

The proportion of the squared passage 39 and the portion 32 of the stud are such that the stud end is readily slidable within this passage to permit assembling or disassembling of the device, there being no positive connection between the stud and the worm at all.

In order to secure the desired adjustment of the knife relative to the plate 15 the outer end of the stud 27 is threaded and has threadedly mounted thereon an adjusting nut 45, with which is associated a cooperating lock nut 46. The nut 45 seats against the outer face of the boss 25, and by proper manipulation of this nut any desired setting of the knife 35 relative to the plate 15 may be secured. By means of this construction

the knife and plate constitute a selfcontained unit and all the thrusts incident to the cutting operation are held within this unit. There will be, during operation, no thrust 5 on the bearing at the back end of the worm except that due to the feeding forward of the meat. And consequently there is no wear on the bearing 12 at the back of the worm when the worm is running idle, and 10 very little when the device is operating to grind meat.

Meats generally contain a considerable percentage of very tough sinews. These are so tough, in fact, that when they protrude 15 through the holes in the plate 15 and the knife comes into contact with them, the knife will tend to slide over the sinews instead of cutting them. In grinders of the types heretofore used this action will actually take place, the knife and perforated plate being forced apart to provide space for these tough sinews. This space is secured by a combination of stretching of the cylinder 10 and compression of the worm 11 25 together with the taking up of slack in the threads on the hand wheel 18, the slack between the knife and plate and the slack between the thrust end of the cylinder and the worm.

30 But in the device of this invention, as shown, the only stretching that can occur is that in the stud 27 so that the action becomes in effect the action of a pair of scissors in which the blades are adjusted tightly 35 against each other. This action results in the clean cutting of the sinews and also prevents clogging of the holes in the plate by reason of their filling up with uncut sinews.

In the device of this invention a further 40 advantage is obtained in that the pressure between the knife and plate may be materially decreased as compared with the standard construction heretofore used. This results in less wear on the knife and plate and 45 also on the rear thrust bearing and also makes for economy in power in operating the chopper as a whole.

By removing the retaining ring 18, through proper manipulation of the hand 50 wheel 19, the plate 15 and knife 35 may be removed as a unit, whenever this is desired.

In order to prevent rotation of the plate, during operation, one edge of the plate is provided with a notch which is adapted to 55 receive the end of a locking pin 50 which is mounted in a suitable passage 51, in the body of the chopper cylinder.

While the form of apparatus herein described constitutes a preferred embodiment 60 of the invention, it is to be understood that the invention is not limited to this precise form of apparatus, and that changes may be made therein without departing from the scope of the invention which is defined in the 65 appended claims.

What is claimed is:

1. In a grinding device of the character described, a chopper cylinder; a worm therein; a flat perforated plate positioned at one end of said cylinder, having an opening 70 therein; a stud mounted in said opening, a knife removably mounted on one end of said stud, and means carried by said stud and independent of said worm for varying the positioning of the plate and knife relative to 75 each other.

2. In a grinding device of the character described, a chopper cylinder; a worm therein; a perforated plate positioned at one end of said cylinder, and having an opening 80 therein, a forwardly extending hollow boss surrounding said opening; a stud mounted within said opening and boss, a knife carried by said stud in driving relation therewith, the end of said stud which extends through said boss being threaded, and an adjusting nut threadedly mounted upon the said stud, in cooperative relation with the said boss.

3. In a grinding device of the character described, a chopper cylinder; a worm therein, having a straight walled socket in one end thereof; a grinding unit comprising a knife positioned in the end of said chopper cylinder, means independent of said worm for maintaining said knife in position, and a driving extension removably associated with said knife extending into the socket in the said worm.

4. In a grinding device of the character 100 described, a chopper cylinder; a worm in said cylinder having a straight walled socket in one end thereof; a plate positioned in one end of said cylinder, and having an opening 105 therein, detachable means for holding said plate in said chopper cylinder; a stud mounted in the opening in said plate, having a squared end positioned in the socket of the said worm, this construction effecting a driving connection between the worm and the stud, a knife mounted on said stud, means for adjusting the stud and the knife carried thereby relative to the plate, independent of the adjustment of the said worm; the construction being such that the 110 plate, stud, and knife may be removed as a unit.

5. In a grinding device of the character described, a chopper cylinder, threaded at one end; a worm mounted in said cylinder, 120 and having a threaded socket in one end thereof, a threaded sleeve, having a squared passage therethrough threadedly mounted within the said socket; a plate positioned against the end of the cylinder, having a centrally arranged opening therein, a co-operating retaining ring threadedly mounted on the threaded end of the said chopper cylinder to hold said plate in position; a 125 forwardly extending boss surrounding the 130

opening in the said plate, a stud mounted in the said opening, the inner end of which is squared, a knife, having a squared passage therethrough, positioned on the squared end 5 of the stud, a retaining flange on the stud, means carried by said stud and cooperating with the plate for clamping the knife between the plate and the retaining flange, and a squared extension on the end of the said 10 stud, beyond the said retaining flange, ex-

tending into the squared passage in the sleeve mounted in the socket in the worm, to effect driving connection between the said worm and the said stud.

In testimony whereof I hereto affix my ¹⁵ signature.

BERNARD M. ELY.
